UNITED STATES PATENT OFFICE.

THOMAS A. GRIFFITH, OF KANSAS CITY, MISSOURI.

CAR-COUPLING.

SPECIFICATION forming part of Letters Patent No. 552,245, dated December 31, 1895.

Application filed March 22, 1895. Serial No. 542,766. (No model.)

To all whom it may concern:

Be it known that I, THOMAS A. GRIFFITH, of Kansas City, Jackson county, Missouri, have invented certain new and useful Improvements in Car-Couplers, of which the following is a full, clear, and exact description, reference being had to the accompanying drawings, forming a part thereof.

My invention relates to what are known as "vertical-plane couplers," and conforms to the contour laid down by the Association of Master Car-Builders.

My object is to eliminate all of the objectionable features of the above-named class of car-couplers. Below said objectionable features receive specific mention.

With the vertical-plane couplers at present in use the guard-arm at one side of the draw-head sustains practically all of the impact by contact with the open coupling jaw or knuckle of the opposing coupler, and consequently a great many couplers are broken in a short time. With the old style, or that at present in general use, having the hook portion of the coupling jaw or knuckle bifurcated, it is evident with two cars having their couplers in different horizontal planes, and therefore having the point or line of resistance in the center, that the lower portion of one of said bifurcated coupling jaws or knuckles is in pulling strain with the upper portion of the mating or opposing coupler, therefore rendering both couplers more susceptible to breakage by providing only a comparatively weak connection.

The coupling jaws or knuckles of vertical-plane couplers are very much weakened by having their hook portion bifurcated and provided with pin-holes for engagement with an ordinary pin and link. This arrangement also provides too much slack or play between the draw-heads, which sometimes results in the breakage of the connections when starting heavy trains.

I have found from a wide experience that about one-half of all the cars equipped with automatic couplers are useless as such when operated by brackets, rods, and chains applied to the ends of the cars, on account of the chains becoming detached or broken, or accidents bending the rods or brackets.

It will be apparent from the following de-

scription, taken in connection with the appended drawings, that I obviate the objectionable features enumerated above. At the close of the description I append, in the form of claims, the features and combinations of parts which I consider new.

Referring to the said drawings, Figure 1 represents a plan view of a pair of vertical-plane couplers in the act of coupling. Fig. 2 is a horizontal sectional view with the coupling jaw or knuckle arranged operatively to receive the ordinary pin and link, which is also shown. Fig. 3 is a horizontal section with the coupling jaw or knuckle in its closed position and with the contiguous parts arranged operatively, one to permit and the other to force said coupling-jaw open in the direction indicated by the arrow to the position shown in dotted lines, same figure. Fig. 4 is a detail perspective view of said coupling jaw or knuckle. Fig. 5 is a vertical section taken on the line 5 5 of Fig. 1 and showing the coupling jaw or knuckle locked in its closed position.

In the said drawings, 1 designates a draw-bar of the usual or customary construction, which terminates at its front end in an enlargement or draw-head at one side formed with the usual guard-arm 2, and segmentally bifurcated, as at 3, to form the upper and lower walls 4 and 5, respectively. Projecting forward in the same vertical plane from said upper and lower walls at the side of the center opposite to that occupied by the guard-arm 2 are bearing lugs or ears 6, which are provided with vertically-aligned circular openings 7. The segmental bifurcation 3 is struck from the axis of said openings. Outward of said openings the upper and lower walls are joined by the bridge-bar 8, so that the bifurcation 3 opens externally of the draw-head at the front end of the same and at one side of the center and contiguous to the guard-arm 2, is provided with a vertical rectangular opening 9, which intersects or is intersected by the segmental cavity 3, as clearly shown. Projecting upwardly from the draw-head at its junction with the draw-bar is the transverse rib 10, from which project forwardly the oppositely-disposed ears 11, in which is rotatably mounted a rod having a

dual function—viz., the lifting of the locking-pin hereinafter described and the opening of the coupling jaw or knuckle, also herein-after described. Said rod comprises the 5 transverse body portion 12, which terminates at one end in the crank-arm 13, and at its opposite end is bent downward to form the handle 14 and inward to form the arm 15, said arm 15 projecting into the bifurcation 3, 10 where it opens at the side of said draw-head, as clearly illustrated.

The coupling rod or knuckle comprises the hook portion or front end 16 and the rear or body portion 17. The hook portion corresponds in thickness to the draw-head, so that 15 its upper and lower surfaces shall be flush or in the same plane as the upper and lower sides of the draw-head, while the rear or body portion 17 fits within the bifurcation 3, so that 20 its upper and lower surfaces shall be contiguous to the inner sides of the upper and lower walls 4 and 5, respectively, of the draw-head. Said body portion is mounted pivotally upon the pin 18, engaging the openings 25 7 of the lugs or ears 6. The body portion, at its junction with the hook portion, is vertically enlarged or thickened, so as to form the forwardly-disposed face 19 and the rearwardly-disposed elongated shoulders 20 and 30 21, which occupy the same horizontal plane as and are adapted to bear squarely against the transverse portions 22 and 23, respectively, of the front edges of the upper and lower walls 4 and 5 of the draw-head, said portions 35 22 and 23 being located at the center of the draw-head and connecting the guard-arm 2 at one end of the bifurcation with the lugs or ears 6. The rear or body portion of the draw-head is segmental in form, being struck 40 from the axis of the pivot 18, and of radius slightly less than that of the bifurcation, so as to fit snugly therein when the coupling jaw or knuckle is in its closed position. Said rear or body portion is also bifurcated to 45 form the upper and lower arms 24 and 25, and said arms contiguous to the shoulders 20 and 21 are notched, as shown at 26 and 27, respectively, and at 28 and 29, respectively. As a result of notching said arms 50 at 28 and 29, they are formed with and connected by a hook 30, which is grooved in its outer side, as at 31. When said coupling jaw or knuckle is in its closed position, as shown 55 at Fig. 3, the notches 26 and 27 thereof register with the rectangular opening 9 of the draw-head, and the hook 30 occupies a position rearward of the bridge portion 8 connecting the upper and lower walls of the draw-head. In the bifurcation of the rear or body 60 portion of the coupling jaw or knuckle an elongated wall or shoulder 32 is formed, lying in the plane of the shoulders 20 and 21, and said shoulder connects with a second shoulder 33, which extends at a suitable angle to the first-mentioned shoulder, and terminates 65 at the inner end of the notches 28 and 29. At a certain point the arms 24 and 25 of the body

or rear portion of the coupling jaw or knuckle are provided with vertically-aligned pin-holes 34.

35 designates a rectangular pin, which is provided at a suitable distance apart with an upper notch 36 and a lower notch 37. It is also provided with a head 38, which is laterally extended at one side, as at 39, so that 70 75 when in operative position relative to the draw-head—that is, when engaging the vertical rectangular opening thereof—said extension 39 shall overhang and rest upon the crank-arm 13 of the rod hereinbefore described. At its lower end said pin is provided with a spring key or cotter 40, which is arranged so that when said pin is elevated it will come in contact with the bottom of the draw-head at the same time that the notches 85 36 and 37 register with the upper and lower arms, respectively, of the rear or body portion of the coupling jaw or knuckle, as shown in dotted lines, Fig. 5. When said coupling jaw or knuckle is in its closed position, as shown at 90 Figs. 1 and 5, said pin also engages the registering notches 26 and 27 of said rear or body portion, and therefore locks it firmly in such position.

When it is desired to couple two draw-heads 95 embodying my invention, one of them occupies the position just described, while the other occupies the position shown in full lines, Fig. 1, and in dotted lines, Fig. 3. To move said coupling jaw or knuckle from its closed 100 position to the opened position shown, it is necessary to grasp the handle portion 14 of the rod hereinafter described and swing it forward until the arm 15 moves to the position shown in Fig. 3. This movement at the 105 same time causes the crank-arm to rise to the position shown in dotted lines, Fig. 5, and elevate the locking-pin a corresponding distance, or until its limit of upward movement has been reached, and the notches 36 and 37 110 of said pin register with the notches 26 and 27 of the arms 24 and 25. The said rod is now forced inwardly in the direction indicated by the arrow, Fig. 3, this operation, as will be readily understood, forcing the coupling jaw 115 or knuckle to the position shown in full lines, Fig. 1, and dotted lines, Fig. 3. The locking-pin remains elevated because the arms 24 and 25 of the coupling jaw or knuckle are in engagement with the notches 36 and 37. It is 120 now manifest, when two of said couplers have their jaws occupying the relative positions described and shown in Fig. 1, that the closed jaw of one engages and pivotally operates the open jaw of the other, until the movement of said jaw is arrested by reason of the shoulders 20 and 21 coming in contact with the transverse portions 22 and 23 of the front edges of the draw-head. At the same time the corresponding portions of the other draw-head resist the impact or thrust of the shoulders 20 and 21 of its coupling jaw or knuckle. Therefore it is evident that the impact incident to the coupling of cars, particularly 125 130 135

freight-cars, with my improved coupling will not be borne by the guard-arm 2, but will be distributed equally upon both draw-heads in the line of draft at their center, where they 5 are strongest. This construction obviates the objectionable feature first enumerated, of most draw-heads of this class.

Immediately the notches 26 and 27 of the coupling jaw or knuckle register with the 10 opening 9 of its corresponding draw-head, the locking-pin 35 by gravity descends to its original position, as shown clearly in Fig. 5, and locks said jaw or knuckle from further movement. It will be apparent by reference 15 particularly to Fig. 5 that the coupling-pin is engaged by the rear or bifurcated portion 17 of the coupling jaw or knuckle, both above and below its center. Therefore it is manifest, should two couplers occupy different 20 horizontal planes, and the lower portion of one coupling jaw or knuckle engage the upper portion of the other, that the pulling-strain upon each coupler is in direct longitudinal alignment with its draw-bar, so that the strain 25 is equally distributed. It will also be observed that it will be practically impossible to injure or break the locking-pins because the jaws or knuckles engage them at two points above and below their centers. This construction, 30 it will be observed, obviates the second objectionable feature hereinbefore enumerated.

When it is necessary to employ my improved coupler in connection with the ordinary pin-and-link coupling, or when it is necessary to connect two of my improved couplers by a pin and link, the coupling jaw or knuckle is moved pivotally to the position shown in Fig. 2, where it will be observed that the jaw bears at its rear side outward of 35 the pivot against the bridge portion 8 of the draw-head, and that the shoulders 32 and 33 extend approximately parallel with and transversely of the line of draft, respectively. The jaw or knuckle is locked in this position 40 by means of the locking-pin 35, which is caused to engage the notches 28 and 29, registering with the opening of the draw-head. The link carried by the approaching draw-head enters between the arms 24 and 25 of the coupling 45 jaw or knuckle, which thus form practically a second draw-head, provided with one side wall or shoulder 32 and a rear wall or shoulder 33. If the coupling-link be too long, the shoulders or walls 33 will receive the impact there- 50 from and relieve the locking-pins of direct and forcible contact with said link. Said locking-pins, of course, sustain the impact at points above and below the center of the jaws or knuckles, as above described. With links 55 of proper length, however, the forwardly-presented portions of the jaws or knuckles at the junction of the hook portions with the rear or body portions 17 will act as buffers, and the impact will be about equally distributed 60 upon the locking-pins and the bridge portions 8. By this construction it will be apparent that I provide, as hereinbefore stated,

practically complete draw-heads for engagement with the ordinary coupling-link without weakening the coupling jaw or knuckle in the 70 slightest degree, thus obviating the third objectionable feature hereinbefore enumerated.

To raise the locking-pin easily and quickly, and to pivotally operate outward the coupling jaw or knuckle when required, I provide 75 the convenient, strong and durable rod, bent as described, which has the necessary rotatable and pivotal movement, and which can be manipulated without intruding any part of the operator's body except his arm between 80 the cars. This construction, it is apparent, obviates the fourth and remaining objectionable feature hereinbefore enumerated, although it is apparent that the usual rock-shaft upon the end of the car, and the chain 85 to connect the same with the coupling-pin, may be employed if preferred.

Slight changes in the detail construction and arrangement of the parts may be made without departing from the spirit and scope 90 or sacrificing any of the advantages of the invention.

Having thus described my invention, what I claim as new, and desire to secure by Letters Patent, is—

1. A car-coupler, comprising a bifurcated drawhead provided with a vertical rectangular opening, a coupling-jaw or knuckle having a bifurcated rear or body-portion provided with vertically aligned notches which are 100 adapted to register with the rectangular opening of the draw-head, a rectangular locking-pin engaging the opening of said draw-head and provided with notches at a distance apart corresponding to the distance between said 105 notches of the bifurcated coupling-jaw or knuckle, and a rod rotatably and slidably mounted upon the draw-head and provided with a crank-arm at one end which detachably engages the locking-pin, substantially 110 as set forth.

2. A car-coupler, comprising a bifurcated draw-head provided with a vertical rectangular opening, a coupling-jaw or knuckle having a bifurcated rear or body-portion having 115 vertically aligned notches, which are adapted to register with the rectangular opening of the draw-head, a rectangular locking-pin engaging the opening of said draw-head and provided with notches at a distance apart corresponding to the distance between said notches of the bifurcated coupling-jaw or knuckle, and a rod slidably carried and provided with an arm projecting into the bifurcated draw-head and against the outer side of said coupling-jaw or knuckle rearward of its pivot, substantially 125 as set forth.

3. A car-coupler, comprising a bifurcated draw-head provided with a vertical rectangular opening, a coupling-jaw or knuckle having a bifurcated rear or body-portion, having 130 vertically aligned notches which are adapted to register with the rectangular opening of the draw-head, and a rod rotatably and slid-

ingly supported, and provided at one end with a crank-arm detachably engaging the locking-pin, and at the opposite end with an inwardly-projecting arm which engages the 5 outer side of the coupling-jaw or knuckle rearward of its pivot, substantially as and for the purpose set forth.

4. A car-coupler, comprising a bifurcated draw-head provided with a vertical rectangular opening, a coupling-jaw or knuckle having a bifurcated rear or body-portion, having vertically aligned notches which are adapted to register with the rectangular opening of the draw-head, and provided also at one side 15 with a groove, and a rod rotatably and slidably supported, and provided at one end with a crank-arm detachably engaging the locking-pin, and at its opposite end with an inwardly-projecting arm which engages the 20 said groove of the coupling-jaw or knuckle rearward of its pivot, substantially as and for the purpose set forth.

5. A car-coupler, comprising a draw-head having a vertical rectangular opening, a 25 guard-arm at one side, and bifurcated to form an upper and a lower wall, and provided with

a bridge-portion connecting said upper and lower walls at the front end and side opposite to that occupied by said guard-arm, a coupling-jaw or knuckle pivoted to said draw-head inward and forward of said bridge-portion, and notched at the side of said pivot contiguous to the center of the draw-head, to form approximately longitudinal and transverse shoulders and upper and lower arms, 30 which are notched at one end of said transverse shoulder, and provided also with vertically aligned openings to receive an ordinary coupling-pin, and a locking-pin engaging the vertical opening of the draw-head and the 35 notched portion of said coupling-jaw or knuckle, and provided with a pair of notches which are adapted to receive at times the upper and lower arms of the said coupling-jaw or knuckle, substantially as set forth. 40

In testimony whereof I affix my signature in the presence of two witnesses.

THOMAS A. GRIFFITH.
